UNITED STATES PATENT OFFICE.

HARRY SAYLES POND, OF CHICAGO, ILLINOIS.

VENDING-MACHINE.

No. 874,236.

Specification of Letters Patent.

Patented Dec. 17, 1907.

Application filed February 18, 1907. Serial No. 357,795.

To all whom it may concern:

Be it known that I, HARRY SAYLES POND, a citizen of the United States, residing at Chicago, in the county of Cook and State of Illinois, have invented new and useful Improvements in Vending-Machines, of which the following is a specification.

This invention relates to coin controlled vending machines and is designed more especially for vending matches in small boxes or packages.

The object of the invention is to provide a strong and substantial vending machine of simple construction and reliable operation which can be manufactured inexpensively, has a large capacity while compact in size and is free from springs and other delicate and complicated parts which might easily get out of order and render the machine inoperative.

Another object of the invention is to provide for a positive delivery of the articles to be vended alternately from two compartments by the use of a single delivery mechanism.

Further objects of the invention are to provide for the discharge of the operating coin at the beginning of the stroke of the delivery mechanism; to prevent the delivery of more than one box at each operation of the delivery mechanism; to carry a box in position for delivery at the same time that a box is delivered; to require the proper and complete operation of the delivery mechanism before a box is delivered; and to construct the machine and mechanism in a way to promote safety in vending matches.

In the accompanying drawings illustrating my invention Figure 1 is a front view of the machine. Fig. 2 is a front view of the interior of the machine, the hinged front being swung to open position. Fig. 3 is a sectional view on the line 3—3 of Fig. 1. Fig. 4 is a vertical sectional view on the line 4—4 of Fig. 3 and shows several positions of a box of matches being delivered from the right hand compartment. Fig. 5 is a similar view showing the several positions of a box of matches being delivered from the left hand compartment. Fig. 6 is a transverse sectional view on the line 6—6 of Fig. 3. Fig. 7 is a similar view on the line 7—7 of Fig. 3. Fig. 8 is a vertical sectional view on the line 8—8 of Fig. 3. Fig. 9 is a detail view of the locking trigger. Fig. 10 is a bottom plan view of the ejector slide.

The invention comprises a cabinet consisting of a front or cover part 11 and a back part 12, the back part being constructed to telescope within the front part, as shown in Fig. 3. The back part of the cabinet contains the goods to be vended and the delivery mechanism, and the front part is hinged at 13 to the back part so that it can be swung down into horizontal open position to permit access to the coin receptacle 14 and to replenish the supply of matches or other articles. The two parts of the cabinet are locked together, preferably at the top, in any suitable manner.

The cabinet forms the subject matter of a companion application filed concurrently herewith and for that reason I make no claim thereto, *per se*, in this application.

The machine which I have chosen for illustrating the invention comprises two storage compartments 15 and two delivery compartments 16, 16', these compartments being formed in the back part of the cabinet by partitions 17, 17' (Fig. 2). The compartments 15 have bottoms 15' which may be made integral with the partitions and the latter can be conveniently constructed of sheet metal in angular form and riveted or otherwise securely fastened within the back part of the cabinet, (Figs. 2, 7).

The coin receptacle 14 is removably arranged in a frame 18 located beneath the delivery compartments 16, 16' and this frame supports the ejector slide 19 which is arranged to reciprocate back and forth from side to side of the cabinet. The slide rests upon the flanges 20 and is held in place by the flanges 21 of the frame 18 (Figs. 3—5). The ejector slide has a central opening 19' and is provided on its upper side with parallel ejectors 22 located at the side edges of said opening and on its lower side with a locking lug 23 and a rack 24 (Fig. 10). The ejector slide also has a handle 25 at its front edge which projects through a slot 26 in the frame 18 and a corresponding slot 26' in the front of the cabinet.

A block 27 is fastened to the frame 18 by screws 27' (Figs. 4, 5) and is provided with a slot 28 (Fig. 3) to receive the coin. The coin is supported in the slot on the arm 29 normally arranged immediately below the slot and carried by a lever 30 pivoted at 31 on the block 27 and enlarged at 32 to provide sufficient weight for swinging the lever to vertical position after it is released as hereafter de-

scribed. The upper end 33 of the lever 30 is arranged to engage the teeth of the rack 24 on the under-side of the ejector slide 19.

A locking trigger 34 (Fig. 9) is pivoted at 5 35 in the slot 28 of the block 27 (Fig. 3). The upper end 34' of the trigger is enlarged to furnish sufficient weight to normally swing said upper end backward in the path of the locking lug 23 on the under-side of the ejector 10 slide. A shoulder 36 on the trigger is arranged to engage a shoulder 37 on the block 27 to hold the trigger in operative position for engaging the locking lug. While the trigger is thus locking the ejector slide by engaging one end thereof the lower end 34'' is 15 swung forward in the slot 28 of the block 27. When the coin 38 is deposited in the slot 28 it engages the end 34'' of the trigger and swings the end 34' out of the path of the locking lug to release the ejector slide. Thereupon the slide can be moved horizontally and when the rack 24 engages the upper end 33 of the lever 30 said lever will be swung to one of the dotted positions shown in Figs. 4, 5, thus 20 carrying the supporting arm 29 from beneath the coin and allowing the coin to fall into the receptacle 14 before the operation of delivering the box of matches is completed. If the movement of the ejector slide is halted 25 before the slide reaches the limit of its movement in either direction a reverse movement will be prevented by reason of the engagement of the end 33 of the lever 30 with the teeth of the rack 24 and thus the movement 30 of the ejector slide in either direction must be completed before its movement can be reversed. If the movement of the ejector slide in either direction is not completed a coin deposited in the machine would fall straight 35 through to the coin receptacle because the supporting arm 29 is in one of the dotted positions shown in Figs. 4, 5.

The front part of the cabinet is provided with a coin opening 39 which is located at the 40 upper end and in front of the coin slot 40 formed between the partitions 17' which separate the compartments 16, 16'. This slot is provided at its lower end with a contracted chute 41 which discharges into the 45 slot 28 in the block 27 (Figs. 1-3). The slot 40 is preferably provided with a plurality of suitably arranged obstructions 42 which cause the coin to travel in a zig-zag direction in the slot and prevent the machine from being cheated by the introduction of wire or 50 strings. An air space 40' is provided between the partitions 17' above the slot 40 to prevent the heat which would be produced by a fire in one delivery compartment from 55 being communicated to the other.

At the lower corners of the front part of the machine are openings 43 to permit the boxes to be removed from the machine after the delivery operation is complete.

60 To enable the purchaser to tell whether the

compartments 16, 16' are empty or supplied with matches I provide openings 44 in the front part of the cabinet opposite the lower part of the compartments 16, 16'. These openings are narrower than match boxes so 70 that a box could not be removed therethrough and both openings are covered by a pane of glass 45 which is held in place on the cabinet by a plate 46 (Fig. 7).

The machine delivers alternately from the 75 compartments 16, 16' and can not operate otherwise for the movement of the ejector slide must be completed in one direction before its movement can be reversed. The delivery operation is illustrated in Figs. 2, 4, 5. 80 In Fig. 2 the ejector slide is shown at the limit of its movement to the right having been moved from beneath the box 47 which has fallen to the bottom of the cabinet opposite the opening 43. The box 47 came from 85 the compartment 16 and a box 48 from compartment 16' has been carried forward from beneath the stack of boxes in said compartment and is held in position to be dropped to the bottom of the cabinet when the ejector 90 slide is carried back again to the limit of its movement to the left. In the movement of the ejector slide the box which is supported like box 48 for delivery engages stops formed by the ends 21' of the flanges 21 and is thus 95 prevented from moving with the slide. The ends of the flanges are preferably upturned and permit the box to be moved thereover from its compartment to delivery position but prevent a return movement of the box so 100 that the slide can move from under the box and permit the latter to drop down to the bottom of the cabinet. Before a box is pushed by the ejectors 22 from beneath the stack the ejectors have passed under to support the stack and therefore it will be observed that the ejectors alternately support the stacks of matches in the two compartments as they push the bottom box from beneath the stack which they then support. 110 By thus delivering boxes alternately from two stacks the capacity of the machine is doubled without materially increasing its size.

In Fig. 4 I have shown the movements of a 115 single box from the compartment 16'. This box 49 is shown in full lines supported on the ejectors; in dotted position 49' behind the ejectors after they have moved to the dotted position at the left and beneath the compartment 16; in dotted position 49'' to which the box is carried in the movement of the ejector slide to the limit of its movement to the right; in dotted position 49''' against the stops 21' and in dotted position 49'''' at the 120 bottom of the cabinet in position behind the opening 43 to be removed by the purchaser. In Fig. 5 the box 50 in compartment 16 is shown in the corresponding positions to those 125 illustrated in reference to box 49 in Fig. 4. 130

While my machine is intended, primarily, for dispensing matches in small boxes of predetermined size it will be apparent to those skilled in the art that it is not limited to this particular use and may be employed for dispensing a variety of articles and whether arranged in boxes or packages or otherwise. The proportion and arrangement of the several parts of the machine can be varied as 10 found desirable to construct the machine in different sizes or to better adapt it for dispensing particular classes of merchandise.

As this machine is designed particularly for vending matches I prefer to make it entirely of metal, the cabinet and frame being 15 made of sheet metal and the other parts of metal castings, preferably. The cabinet is preferably of such depth as to hold boxes lengthwise in the compartments and when 20 the cabinet is closed a box of matches, if ignited accidentally, will simply smolder without igniting adjacent boxes ordinarily and even if several boxes in a compartment become ignited the fire will not communicate 25 to those boxes in the other compartments. The outer compartments can be utilized for storage purposes.

It will be observed that the ejector slide not only carries the ejectors to move the 30 boxes alternately from the compartments 16, 16' but it also comprises a table 51 at each end of the slide. The box being moved from its compartment by the ejectors is supported on one table and the stack of boxes in 35 the other compartment is supported on the flanges 21 above the table at the other end of the slide and when the movement of the slide is reversed this box which is supported on the flanges is pushed outward by the ejectors on 40 its table.

A box will not be discharged from the slide until the latter has been moved far enough to release the lever 30 from rack 24, because the 45 bottom flange 15' of the storage compartment will prevent the box from tilting sufficiently to slip off of the slide until the latter has been properly operated. This insures the proper operation of the delivery mechanism and avoids the liability of the machine 50 being left in an inoperative position, while at the same time is free from springs or complicated parts which may quickly get out of order.

The handle 25 is curved so that the front 55 of the cabinet can be swung to open or closed position without affecting the delivery mechanism. The front of the cabinet also forms the front wall of the compartments and secures the coin receptacle in place.

60 What I claim and desire to secure by Letters Patent is:

1. A vending machine comprising a cabinet having two compartments for the articles to be vended, and a single delivery mechanism for said compartments com-

prising an ejector slide adapted to be reciprocated beneath said compartments, there being tables on said slide at each end thereof, and an ejector on the slide between said tables to move the articles alternately from 70 said compartments on said tables.

2. A vending machine comprising a cabinet having two compartments for the articles to be vended, and a single delivery mechanism for said compartments comprising an 75 ejector slide adapted to be reciprocated beneath said compartments, there being a table on said slide at each end thereof, and a pair of ejectors located between said tables and at opposite sides of said slide to move 80 the articles alternately from said compartments.

3. A vending machine comprising a cabinet having two compartments for the articles to be vended, and a single delivery mechanism for said compartments comprising a 85 slide adapted to be reciprocated beneath said compartments, there being a table on said slide at each end thereof, an ejector carried by the slide between said tables to 90 move the articles alternately from said compartments on said tables, and a device for locking said slide at the limit of its movement in either direction with one table beneath one of said compartments, the ejector 95 beneath the other compartment and the other table supporting one of the articles from the last mentioned compartment in position to be delivered on the return movement of the slide.

4. A vending machine comprising a cabinet having two compartments for the articles to be vended, and a single delivery mechanism for said compartments comprising a 100 slide adapted to be reciprocated beneath said compartments, there being a table on said slide at each end thereof, an ejector on the slide between said tables to move the articles alternately from said compartments on 105 said tables, and means for discharging articles from said tables.

5. A vending machine comprising a cabinet having two compartments for the articles to be vended, and a single delivery mechanism for said compartments comprising a 110 slide adapted to be reciprocated beneath said compartments, there being a table on said slide at each end thereof, an ejector on the slide between the tables to move the articles from the compartments alternately on 115 the tables, and means for discharging the article on one table from one compartment as the ejector travels in the opposite direction to move an article from the other compartment on the other table into discharge 120 position.

6. A vending machine comprising a cabinet having two compartments for the articles to be vended, and a single delivery mechanism for said compartments comprising a 125 130

slide adapted to be reciprocated beneath said compartments, there being a table on said slide at each end thereof, an ejector on the slide to move the articles alternately from 5 said compartments on said tables, means for discharging the articles from the tables, means for locking the slide at the limit of its movement in either direction, and means for preventing reverse movement of the slide 10 until it has reached the limit of its movement in either direction.

7. A vending machine comprising a cabinet having two compartments for the articles to be vended, and a single delivery mechanism for said compartments comprising a slide adapted to be reciprocated beneath said compartments, there being a table on said slide at each end thereof, an ejector on the slide between said tables, a locking lug on 15 the slide, a trigger arranged to engage said lug to lock the slide at the limit of its movement in either direction, and means for preventing reverse movement of the slide until it has reached the limit of its movement in 20 either direction.

8. A vending machine comprising a cabinet having two compartments for the articles to be vended, and a single delivery mechanism for said compartments comprising a slide adapted to be reciprocated beneath said compartments, there being a table on said slide at each end thereof, an ejector on the slide between said tables, means for locking the slide at the limit of its movement in 30 either direction, a rack on the slide, and a lever arranged to engage said rack to prevent reverse movement of the slide until it has reached the limit of its movement in 35 either direction.

40 9. A vending machine comprising a cabinet having two compartments for the articles to be vended, and a single delivery mechanism for said compartments comprising a

slide adapted to be reciprocated beneath said compartments, there being a table on said slide at each end thereof, an ejector on the slide between said tables to move the articles alternately from said compartments on said tables, and means for discharging an article moved on one table from one compartment 50 as the ejector is moving an article from the other compartment on the other table.

10. A vending machine comprising a cabinet having two compartments, a frame beneath the compartments, a slide adapted to 55 be reciprocated on the frame, there being flanges on the frame forming guides for the slide and stops to prevent return movement of the articles, and said slide having a table at each end thereof and an ejector located 60 between the tables.

11. A vending machine comprising a cabinet having a delivery compartment therein to receive the articles to be vended, a delivery mechanism operating beneath said compartment and comprising a movable slide on which the article to be delivered rests in delivery position, and means for preventing the discharge of the article from the slide until the latter has been moved a predetermined 70 distance.

12. A vending machine comprising a cabinet having a plurality of compartments therein to receive the articles to be vended, a delivery mechanism operating below the 75 compartments and comprising a movable slide on which the article to be delivered rests in delivery position, and a bottom to one of said compartments to prevent the discharge of the article from the slide until the 80 latter has been moved a predetermined distance.
